UNITED STATES PATENT OFFICE.

WILLIAM B. SMITH, OF LAWRENCEVILLE, ILLINOIS.

TANK-CAR HEATER.

1,412,756.

Specification of Letters Patent. Patented Apr. 11, 1922.

Application filed January 26, 1921. Serial No. 440,246.

To all whom it may concern:

Be it known that I, WILLIAM B. SMITH, a citizen of the United States, and a resident of Lawrenceville, in the county of Lawrence 5 and State of Illinois, have invented a new and useful Tank-Car Heater, of which the following is a specification.

My invention is a tank car heater and has as its all important object the provision of 10 a heater of this character for heating the liquid contents of the car such as heavy oils to a temperature where the same may be readily dispensed or drawn from the car.

Further the invention embodies a tank car 15 heater which will be securely anchored in the tank and is so constructed as to prevent leakage of the steam or other heating agent which usually results in the damaging of the contents of the tank.

It is a further object of the invention to 20 provide a heater of this character which may be readily taken from the tank for repairs and then replaced and which will also permit the tank to be repaired and cleaned.

Still another object of my invention embodies a tank car heater heated through the 25 medium of steam and which is so constructed as to obviate bursting of the heater pipes due to freezing of condensed steam therein.

With the preceding and other objects and 30 advantages in mind, the invention consists in the novel combination of elements, constructions and arrangements of parts and operations to be hereinafter enlarged upon, 35 claimed and illustrated in the accompanying drawings, wherein:

Figure 1 is a view partly in longitudinal 35 section and partly in elevation of a tank car equipped with my heater;

Figure 2 is a vertical sectional view of the 40 same;

Figure 3 is a top plan view, parts of the 45 tank being shown in broken lines and parts of the heater being broken away; and

Figure 4 is a fragmentary transverse sectional view taken on line 4—4 of Figure 3.

Referring in detail to the drawings wherein like characters of reference designate corresponding parts throughout the several 50 views, the numeral 5 designates a modern tank car to which my improved heater is applied and which includes a plurality of longitudinally bowed headers 6 placed upon the bottom of the tank and disposed transverse-

ly thereof. Each of these headers is provided with laterally disposed ears or feet 7 at their ends which are removably fastened to the walls of the tank by fastenings 8.

Parallel tubes 9 extend from one of the intermediate headers to the other while 60 tubes 10 extend from these intermediate headers to the end headers. The headers 6 are provided with plugged openings 11, the plugs of which may be removed to permit additional pipes to be employed if desired.

The intermediate headers are formed with nipples 12 at their crest, one of which communicates with a steam pipe 13 extending vertically through the bottom of the tank while the other communicates with an outlet pipe 14 also extending vertically through 65 the bottom of the tank.

The bottom of the tank is provided with the usual control valve in its bottom and is designated in its entirety at 15. It will be 70 obvious that steam or other heating fluid passing through the pipe 13 will circulate through the headers and tubes and pass out by way of the pipe 14, and as these tubes are 75 submerged in the fluid contained in the tank car, this fluid will be retained at such temperature as to permit the same to be readily drawn from the tank.

It is to be understood that the form of my 80 invention herein shown and described is to be taken as a preferred example of the same, and that various changes in the shape, size and arrangement of parts may be resorted to without departing from the spirit 85 of the invention or the scope of the subjoined claim.

Having thus described my invention, what 90 I claim as new and desire to secure and protect by Letters Patent of the United States, 95 is:—

The combination with a tank car, of a plurality of longitudinally bowed headers arranged transversely of the bottom of the tank, feet carried by the ends of the headers and detachably secured to the tank, longitudinally arranged heating tubes communicating with the headers for heating the liquid contained in the tank, a steam pipe passing vertically through the bottom of the tank and having communication with one of the headers, and an outlet pipe communicating 100 with one of the remaining headers.

WILLIAM B. SMITH.
